UNITED STATES PATENT OFFICE.

JOHN LENCE, OF REGINA, SASKATCHEWAN, CANADA.

WASHING, SCRUBBING, AND DRYING MACHINE.

Application filed May 4, 1920, Serial No. 378,764. Renewed May 1, 1922. Serial No. 557,559.

To all whom it may concern:

Be it known that I, JOHN LENCE, a subject of the King of Great Britain, residing at Regina, in the Province of Saskatchewan and Dominion of Canada, have invented certain new and useful Improvements in Washing, Scrubbing, and Drying Machines, of which the following is a specification.

This invention relates to machines for 10 washing, scrubbing and drying floors, and the primary object of the invention is to provide an improved machine which will effectively wash, scrub and dry a floor without the necessity of a person washing the 15 floor getting on their hands and knees.

Another object of the invention is to provide an improved floor washing, scrubbing and drying machine which will permit of floors being quickly and thoroughly cleaned 20 and which entirely eliminates the usual labor associated therewith.

A further object of the invention is the provision of an improved floor cleaning machine embodying an endless washing cloth, 25 an endless drying cloth, and a rotary scrubbing brush arranged between the cloths, the washing and drying cloths having means for permitting the dirty water to be removed therefrom, the washing cloth also having 30 means for regulating the amount of clean water carrier thereby.

A still further object of the invention is the provision of an improved floor washing machine of the above character which is durable and efficient in use, one that is simple 35 and easy to manufacture, and one which can be placed upon the market at a reasonable cost.

With these and other objects in view, the 40 invention consists in the novel construction, arrangement and formation of parts as will be hereinafter more fully described, claimed and illustrated in the accompanying drawings, forming a part of this specification, 45 in which drawings:

Figure 1 is a side elevation of the improved floor cleaning machine.

Figure 2 is a longitudinal section through the same.

Figure 3 is an end elevation of the machine showing parts thereof in section.

Figure 4 is a transverse section through the improved machine.

Figure 5 is an enlarged fragmentary detail side elevation of the improved machine showing the means for adjusting one of the

wringer rollers so as to effectively squeeze the dirt and water from the washing and drying cloths.

Figure 6 is an enlarged fragmentary detail horizontal section through the machine illustrating the means for adjusting the position of the rollers, for regulating the amount of water carried by the washing cloth, in relation to each other. 60

Referring to the drawings, in detail, wherein similar reference characters designate corresponding parts throughout the several views, the letter A indicates the improved washing, scrubbing and drying machine and the same includes a frame B which supports the floor washing device C, the scrubbing device D and the drying device E. 70

The frame B includes a pair of parallel spaced longitudinally extending side bars 10 and the end bars 11, which have their inner faces inclined as at 12 for a purpose which will hereinafter more fully appear. The longitudinally extending bars 10 adjacent to their outer ends support the upstanding vertically disposed bars 13 which support the side walls 14. The side walls 14 may be of any preferred material, either of wood, or sheet metal. The side walls 14 terminate short of the front portion of the longitudinally extending bars 10 as clearly shown in the drawings and the front vertical bars are braced against movement by diagonally extending inclined front brace bars 15. 75

The improved washing device C is arranged at the forward end of the machine and includes an endless cloth 16 and a substantially V-shaped water receiving tank 17 into which the endless belt 16 is adapted to extend so that the belt may be thoroughly 90

saturated with the cleaning fluid before coming into contact with the floor or other surface to be cleaned. It is to be understood that the tank 17 can receive any suitable or desired cleaning fluid such as hot soapy 95 water. The lower end of the endless belt 16 is trained around a transversely extending roller 18 which holds the belt into engagement with the surface to be cleaned and this roller 18 may be made of any desired 100

material either flexible or non-flexible. The roller 18 is rotatably carried by a pair of spaced arms 19 which are pivoted intermediate their ends upon pins 20 which are carried by the longitudinally extending bars 10 adjacent to their forward ends. Oppositely extending coil springs 21 are secured 105

to the upper ends of the arms 19 and these coil springs normally tend to hold the roller 18 in correct position in relation to the floor and at the same time permits the 5 belt to be raised or lowered within certain limits so as to conform to any irregularities in the surface being cleaned. The springs 21 have one of the terminals secured to the arm 19 and their opposite terminals secured 10 to the frame of the machine. A guide roller 22 is rotatably supported by the walls of the tank 17 and is located adjacent to the lower end thereof so that the belt will pass through the cleaning fluid. The guide rollers 23 and 24 are also carried by the side walls of the tank and these rollers are arranged adjacent to the front and rear ends 15 of the tank so as to effectively guide the belt in and out of the tank. A wringer 25 is arranged directly below the guide roller 23 and the endless belt passes between the rollers thereof and this wringer forms means for effectively squeezing the dirt and water from the belt. A means 26 is arranged below and in front of the guide roller 24 for regulating the amount of the cleaning fluid carried by the belt and this means consists 20 of a pair of rollers 27 and 28, which engage the upper and lower surfaces of the belt. 25 The roller 28 has its terminals rotatably carried by the side walls 14. The upper roller 27 has its terminals mounted in sliding blocks 29 which are carried by frames 30 secured to the side walls 14. The blocks 35 are normally held in a raised position by springs 31 and adjusting screws 32 are provided for engaging the blocks 29 for normally urging the same downward in the frame. Thus it can be seen that by adjusting the screws 32 the pressure which the roller 27 bears against the roller 28 can be 40 readily adjusted thereby permitting the quantity of cleaning fluid squeezed from the cloth to be regulated.

45 The longitudinally extending side bars 10 carry the depending bearings 33 which are located on the opposite sides of the transverse center of the machine and these bearings rotatably carry the supporting shafts 34 for the traction wheels 35. Certain of the traction wheels 35 have relatively large sprocket wheels 36 secured thereto, around 50 which is trained a drive sprocket chain 37 for a purpose which will hereinafter more 55 fully appear.

Located intermediate the pairs of traction wheels 35 is the scrubbing device D which includes a rotary brush 38. The brush 38 consists of a roller 39 which carries a plurality of spaced rows of spirally arranged 60 bristles 40 and the roller carries a shaft 41 the terminals of which are rotatably mounted in a suitable substantially inverted U-shaped bracket 42 which is secured to a centrally disposed transversely extending beam

43. The shaft 41 has secured thereto a sprocket wheel 44 and this sprocket wheel engages the lower run of the drive sprocket chain 37. Thus it can be seen that when the machine is pushed over a surface to be 70 cleaned that the scrubbing brush 38 will be rotated therewith. One end of the shaft 41 is extended beyond its bearing and carries a pair of spaced sprocket wheels 45 and 46 for a purpose which will hereinafter more 75 fully appear.

The floor drying device E is arranged directly in rear of the scrubbing brush 38 and the same includes an endless belt 47 the lower end of which is held into tight engagement with the ground by a transversely extending roller 48 which can be made of any preferred material, either of rubber, wood or the like and this roller is rotatably carried by arms 49 which are slidably carried by the side beams 10. The arms 49 are normally held in lowered position so as to hold the roller 48 into tight engagement with the belt 47 by means of contractile coil springs 50 which have one of their terminals secured to the arms 49 and their opposite terminals to pins carried by the side beams 10. A roller 51 is arranged adjacent to the bottom of a substantially V-shaped tank 52 which is arranged adjacent to the rear end 95 of the machine and this roller 51 provides means for guiding the belt 47 adjacent to the lower end of the tank. Guide rollers 53 and 54 are arranged adjacent to the front and rear portions of the tank of the upper ends 100 thereof, so as to guide the belt into and out of the tank. A wringer 55 is carried by the side walls 14 and is arranged directly in front of the guide roller 54 and thus it can be seen that as the belt 47 comes out of 105 the tank 52 all water will be effectively squeezed from the belt 47.

The wringers 25 and 55 for the endless belts 16 and 47 are constructed identically the same and each includes upper and lower 110 rollers 56 and 57. The lower roller 57 is rotatably carried by the side walls 14 while the upper roller 56 is rotatably carried by the sliding blocks 58 which are mounted in frames 59 secured to the side walls 14. The 115 sliding blocks 58 are normally held in a raised position by means of coil springs 60 and the thumb screws 61 are provided for normally moving the roller 56 away from the roller 57. Thus it can be seen that by 120 adjusting the thumb screws 61 the pressure of the roller 56 can be adjusted against the roller 57.

To provide a means for driving the endless belts 16 and 47 the lower rollers 57 of 125 the wringers 25 and 55 have operatively connected thereto sprocket wheels 62 and 63 and sprocket chains 64 and 65 are trained around respectively the sprocket wheels 62 and 46 and 63 and 45. Thus when the trac- 130

tion wheels 35 are rotated the brush 38 and the belts 16 and 47 will be operated.

Each of the tanks 17 and 52 are provided with drain valves 66 and 67 and these valves permit all water to be drained from the tanks when desired.

In operation of the improved machine the desired quantity of cleaning fluid is placed in the tank 17 and the machine is then pushed over the surface to be cleaned. The endless belt 16 passing through the tank 17 will carry a portion of the cleaning fluid therewith, the amount of which is regulated by the rollers 27 and 28. The endless belt 16 comes into contact with the surface to be cleaned and effectively washes the same and as the belt returns to the tank 17 the wringer 25 squeezes all of the dirty water therefrom. After the surface to be cleaned has been acted upon by the belt 16 the rotary brush 38 will come into contact with and thoroughly brush the surface, after which the drying belt 47 engages the surface and effectively dries or mops the same. As the endless belt 47 travels through the tank 52 the wringer 55 squeezes all of the dirty water therefrom and when the portion from which the water has been squeezed again comes into contact with the surface being cleaned the same will absorb more of the water.

Changes in details may be made without departing from the spirit or scope of the invention; but,

I claim:

1. A floor cleaning machine comprising a frame, supporting wheels for the frame, a pair of tanks arranged adjacent to the opposite ends of the frame, a rotary brush arranged to engage the surface to be cleaned carried by the frame and arranged intermediate the tanks, an endless washing cloth carried by the frame and arranged to extend through one of the tanks, means for resiliently holding the lower end of the endless washing cloth in engagement with the surface to be cleaned, an endless drying cloth carried by the opposite end of the machine and arranged to extend through the other tank, resilient means for holding the lower end of the drying cloth in engagement with the surface to be cleaned and means for operatively connecting the rotary brush and washing and drying cloths with the traction wheels so as to permit the operation thereof when the machine is pushed over the surface to be cleaned.

2. A floor cleaning machine comprising

a frame, pairs of spaced supporting wheels carried by the frame, a rotary scrubbing brush arranged transversely of the frame and carried by the frame, spaced sprocket wheels carried by the brush, sprocket wheels carried by the supporting wheels, a traction chain trained around the sprocket wheels carried by the supporting wheels and arranged to engage one of the sprocket wheels carried by the rotary brush, endless washing and drying cloths arranged at the opposite ends of the machine, spring pressed guide rollers arranged to normally hold the endless washing and drying cloth in engagement with the surface being cleaned, guide rollers carried by the frame, sprocket wheels carried by certain of the guide rollers, and sprocket chains trained around said sprocket wheels carried by the guide rollers and around the other sprocket wheels carried by the brush.

3. A floor cleaning machine comprising a frame, pairs of spaced supporting wheels carried by the frame, tanks arranged on opposite ends of the frame, a transversely extending scrubbing brush carried by the frame and arranged intermediate the pairs of supporting wheels, an endless washing cloth arranged at the front of the machine, guide rollers arranged to guide said washing cloth through the tank, means carried by the forward end of the machine for holding the washing cloth in engagement with the surface to be cleaned, means for regulating the quantity of water carried by the washing cloth, means for squeezing the dirty water out of the washing cloth, a drying cloth carried by the rear end of the machine, guide rollers arranged to guide said drying cloth through the other tank, a wringer arranged to squeeze the dirty water from the cloth and spring pressed means for holding the cloth in engagement with the surface to be cleaned.

4. A floor cleaning machine comprising a wheeled frame, a pair of spaced tanks carried by the opposite ends of the frame, a rotary brush carried by the frame, an endless washing cloth carried by the frame positioned in front of the rotary brush and arranged to extend through one of the tanks, an endless drying cloth carried by the frame in rear of said rotary brush and arranged to extend through the other of said tanks, and means for operating said brush and said cloths.

JOHN LENCE.
